SIGNALING SYSTEM FOR RAILROADS

Jerry Bennett, Scottsville, N. Y., assignor to
General Railway Signal Company, Rochester,
N. Y.

Application April 30, 1932, Serial No. 608,507

19 Claims. (Cl. 246—45)

This invention relates to signal systems for railways, and more particularly to a signal system of the three-position polarized control type.

In a polarized control type signaling system of the three-position or three-condition type, the control circuit for one signal is pole changed as the signal next in advance changes from a proceed to a danger position, or vice versa, and if no special provision is made the control circuit next in the rear will be momentarily opened when the signal changes from a clear to a caution position or vice versa, and this opening of the control circuit, which may cause what is known in signal parlance as a kick-off (which

5 consists of a momentary flash of a red signal from one signal to the next in the rear along the entire railway system unless there is an intervening train to break up the control connection between two adjacent signals) is very annoying, 10 and may in fact cause an accident due to confusion of the engineer.

In accordance with the present invention it is proposed to provide a stick relay, which maintains the continuity of a control circuit in spite of a clear-to-caution or caution-to-clear change of the signal next in advance. This stick relay is so controlled that the safety of the system is not impaired, and further this stick relay serves the additional auxiliary function of affording approach lighting for its associated signal. By approach lighting is meant the lighting of the signal only during the approach of the train; this relay therefore also serves as an energy saving device.

Other objects, purposes and characteristic features of the present invention will in part be obvious from the accompanying drawing and will in part be more specifically described hereinafter.

In describing the invention in detail reference will be made to the accompanying drawing, in which:

Fig. 1 shows the invention applied to a three-position search-light type signal;

Figs. 2, 3 and 4 illustrate this search-light type signal assuming the clear, the caution and the danger position, respectively;

Fig. 5 shows the invention applied to a three-aspect color light signal controlled by a direct current polar neutral relay; and—

Fig. 6 shows a modified form of the system shown in Fig. 5.

Referring to Fig. 1 of the drawing the track rails 1 have been shown divided into blocks by insulating joints 2, of which the block I and the

adjacent ends of the blocks H and J have only been shown. At the entrance end to each block is shown a search-light type signal, the signal at the entrance to the block I being designated S, and the signal at the entrance to the block J being designated S¹. Since the apparatus associated with each of these signals is the same it will suffice to describe only one of these signals, like parts of the other signals being designated by like reference characters having distinctive exponents. Each of the blocks is provided with the usual track circuit, which for the block I includes the track battery 3, the usual series resistance 4 and the track relay T.

The search-light type signal is one in which a reflector is employed in the rear of the signal lamp, which reflector causes the reflected light to focus at a point a short distance in front of the lamp; at a point just beyond this focus the light is again concentrated by the usual roundel of the signal, as a result of which a very small multiple color spectacle may be used to filter the light beam to leave light of a green, yellow or red color for manifesting clear, caution and danger respectively. Since the color spectacle is very small and requires very little energy for operation, this spectacle is operated directly by relay mechanism, which has been shown conventionally.

Referring to Figs. 2, 3 and 4 the movable element has been designated 5, which is controlled in accordance with the polarity of the direct current in the winding 7 which is normally energized by direct current of a particular polarity. This rotor 5, preferably constituting a polar armature, has been shown carrying a spectacle containing a green lens G, a red lens R and a yellow lens Y, which color filters are located in the focus of the light beam when the signal assumes respectively, the clear, the danger and the caution position.

These search-light type signals contain movable contacts 10 and 11, of which the contact 10 is under clear position of the signal in engagement with the stationary contact 12 but under danger or caution position in engagement with the stationary contact 13, whereas the contact 11 is under caution position in engagement with the stationary contact 14 but is under clear and danger conditions in engagement with the stationary contact 15, all as clearly shown in Figs. 2, 3 and 4. Each of these search-light type signals includes a lamp L, which is normally extinguished by reason of the energized condition of the stick relay SR, all in a manner more particularly de-

scribed in connection with the operation of the system.

Operation

Under normal clear traffic conditions the winding 7 of the signal S is energized through the following circuit:—beginning at the positive terminal of the split battery 20¹, wire 21¹, front contact 22¹, wires 23¹ and 24¹, winding of the relay SR¹, wires 25¹ and 26¹, contacts 12¹ and 10¹, wires 27¹ and 28, front contact 29 of the track relay T, wire 30, winding 1 of the signal S, wires 31, 32, common return wire C, wires 32¹ and 33¹ back to the midpoint of the battery 20¹. There is also an auxiliary circuit for energizing the winding 7 of the signal S under normal clear traffic conditions in advance, and this auxiliary circuit is the same as the circuit just traced, except that the stick contact 36¹ and its associated wires 35¹ and 37¹ are substituted for the contact 10¹—12¹ and its associated wires 26¹ and 27¹ of the signal S.

It should thus be noted that the stick relay SR¹ is a series relay, and that it is included in series with the winding 7 of the signal S next in the rear. Also, it should be noted that operation of the contacts 10¹ and 11¹ of the signal S¹ cannot cause deenergization of the winding 7 of the signal S, because the circuit through the stick contact 36¹ will remain intact irrespective of the position of the contacts 10¹ and 11¹ of the signal S¹. It may, however, be pointed out at this time that should the signal S¹ assume the danger position (as shown in Fig. 4) the stick relay SR¹ would be shunted through the following shunting branch:—beginning at the left-hand terminal 24¹ of the relay SR¹, wire 40¹, front contact 41¹ of the relay SR¹, wire 42¹, contacts 11¹—15¹, wire 43¹, contacts 13¹—10¹, wires 27¹ and 37¹, stick contact 36¹, wire 35¹ to the other terminal 25¹ of the stick relay SR¹. Completion of this shunting circuit will not, however, effect deenergization of relay SR¹ unless this shunt is maintained for an appreciable period of time, because the relay SR¹ will be rendered slow dropping by reason of having its swindling closed through a circuit of low resistance, so that rapid reversal of the signal from its clear to its caution position or vice versa will not result in dropping the stick relay SR¹. It may be pointed out that this shunting branch circuit has been provided to assure movement of the signal S to the stop position in the event that a break should occur in the line wire 28¹ of the signal next in advance, to thus de-energize 7¹ and put S¹ to stop, (block J being assumed unoccupied) for under this condition the track relay T¹ would be up and therefore the contact 22¹ would remain closed. If, on the other hand, this safety feature is not desired, this shunting circuit may be omitted, the track relay T¹ and its contacts 29¹ and 22¹ being relied upon to manifest occupancy of the block J.

Let us now assume that a train is moving in the normal direction of traffic as indicated by the arrow, in the block H. The presence of this train in the block H will result in deenergization of the track relay T⁰ (not shown), and thereby break the energizing circuit for the stick relay SR, so that this stick relay SR assumes its deenergized position. With the relay SR deenergized the lamp L of the signal S will be illuminated through energization of the following circuit:—beginning at the terminal B of a suitable battery, back contact 45 of the relay SR, wire 46, signal lamp L to the other terminal (—) of the same battery. The signal S will thus display a green light thereby

informing the engineer on the approaching train that traffic conditions in advance are clear.

As this train progresses into the block I it will shunt the track relay T, and thereby cause it to open its contacts 22 and 29, as a result of which the winding 7 of the signal S is deenergized and the signal S assumes the danger position (see Fig. 4), and displays a red indication because the relay SR is still in its retracted condition with its contact 45 closed. Also, dropping of the contact 29 of the track relay T not only results in deenergizing the winding 7 of the signal S, but also results in deenergizing the winding of the stick relay SR¹ at the next signal in advance, so that the lamp L¹ of this signal S¹ is illuminated for 15 reasons already pointed out in connection with the signal S. Furthermore dropping of track relay T by opening of contact 22 prevents closure of a pick-up circuit for relay SR, so that relay SR remains deenergized and lamp L remains energized until the train leaves block I to permit picking up of track relay T.

As the train in question now progresses into the block J, the track relay T¹ is deenergized and puts the signal S¹ to stop. As soon as the rear end of the train has entirely left the block I, the track relay T will again pick up, and under this condition the winding 7 of the signal S will be energized by current of negative polarity through the following circuit:—beginning at the negative terminal of the battery 20¹, wire 50¹, back contact 41¹ of the relay SR¹, wire 42¹, contacts 15¹—11¹, wire 43¹, contacts 13¹—10¹, wires 27¹ and 28, front contact 29 of the track relay T, wire 30, winding 7 of the signal S, wires 31, 32, C, 32¹ and 33¹ to 35 the midpoint of the battery 20¹. Since the relay SR is still deenergized and its contact 45 is still closed the lamp L is still lighted and a yellow caution signal is displayed. A moment later, however, this picking up of track relay T causes its contact to pick up the relay SR through a pick-up circuit including contacts 11 and 12 to the left (see Fig. 3) after which these contacts 11 and 12 are shunted by front contact 36 of relay SR. This picking up of relay SR extinguishes the lamp L, leaving the signal S dark until a second train approaches. As soon as the train in question entirely leaves the block J the track relay T¹ will reclose its contacts 22¹ and 29¹, as a result of which the stick relay SR¹ is again picked up through the following circuit (the signal S¹ now assuming its caution position):—beginning at the positive terminal of the battery 20¹, wire 21¹, front contact 22¹ of the track relay T¹, wires 23¹ and 24¹, winding of the relay SR¹, wires 25¹ and 26¹, contacts 14¹—11¹, wire 43¹, contacts 13¹—10¹, wires 27¹ and 28, front contact 29 of the track relay T, wire 30, winding 7 of the signal S, wires 31, 32, C, 32¹ and 33¹ back to the midpoint of the battery 20¹. Also, as the train passes entirely out of the block J (resulting in returning of the signal S¹ to the caution position and the movement of contacts 11¹ and 12¹ to the left, and in energization of relay SR¹) current from the positive terminal 21¹ of battery 20¹ may flow to the winding 7 of relay S. This flow of current causes the spectacle of signal S to move to the clear position, but instead of displaying a green signal a dark signal is displayed, because the open contact 45 of relay SR keeps the lamp L deenergized. As the train in question passes out of the next block in advance of the block J, the polarity of the current flow in the winding 7¹ of the signal S¹ will be changed from negative to positive, so that the signal S¹ will change from caution to clear 75

(see Figs. 2 and 3), but this rapid change of the signal S from caution to clear will not in any way disturb the energizing circuit for the winding of signal S, this because the auxiliary circuit includes the stick contact 36¹ of the relay SR¹. Also, although the stick relay SR¹ may be momentarily shunted, this momentary shunt will not result in dropping of the stick relay SR¹.

Modification Fig. 5

10. The present invention, as illustrated in Fig. 5, has been shown applied to a three-aspect color light signal, in which three separate signal lamps colored green, yellow and red, respectively, have 15 been designated by the letters G, Y and R, and this color light signal S² is controlled through the medium of the neutral contact 51 and polar contact 52 of the polar-neutral relay LR in the usual manner well understood by those skilled in the 20 art, the common wire for these lamps G, Y and R being carried through the back contact 45², in exactly the same way as is true of the lamp L of the signal S (see Fig. 1). Since the polar neutral relay LR is controlled in exactly the same 25 manner as is the winding 1 of the signal S, like circuit wires and contacts have been designated with like reference characters having distinctive exponents 2. Also, since the operation of the system shown in Fig. 5 is exactly the same as 30 that shown in Fig. 1 it will be unnecessary to specifically describe the same. In this connection it should be noted that the neutral contact 10²—11² of relay LR engages contacts 13²—15² under de- 35 energized condition of this relay, the same as contacts 10 and 11 of signal S engage contacts 13 and 15, and that during the energized condition of relay LR the contact 10²—11² of relay LR engages contacts 12²—14² the same as contacts 10 or 11 engage, respectively, contacts 12 or 14, and 40 the circuits completed are in each case, equivalents.

Modification Fig. 6

45. Referring to Fig. 5, if desired, instead of using a stick relay SR² a slow acting non-stick relay SL may be used, as shown in Fig. 6. It will be noted that the stick contact 36² has been omitted. With the stick contact 36² omitted the relay SL will be controlled directly by the contact 10³—11³ of the relay LR, so that the contact 22² (see Fig. 5) of 50 track relay T² may also be omitted. Pole-changing of the circuit for the line relay LR will result in momentary dropping of the contact 10³—11³, but since the relay SL is slow dropping, current of negative polarity will not be applied through 55 its back contact 41³ to the next line relay in the rear and no kick-off will result.

Having thus shown and described several specific embodiments of the present invention it is desired to be understood that the specific circuit arrangements and structures illustrated, have not been selected for the purpose of showing the scope of the invention nor the exact construction preferably employed in practicing the same, but that the structure has been selected for the purpose 60 of disclosing the nature of the invention and the manner in which it may be employed in practice, and it is desired to be understood that various changes, modifications and additions may be made to adapt the invention to the particular problem encountered in practicing the same, all without departing from the spirit or scope of the invention or the idea of means underlying the same, except as demanded by the scope of the following claims.

75. What I claim as new is:

1. In a railway signaling system of the direct current polar type; the combination with three condition signals at each of a plurality of points along the track; of a three condition polarity responsive device for each signal; two circuits for each polarity responsive device one energized by current of one polarity and the other energized by current of another polarity and each including contacts of the next polarity responsive device in advance; and an auxiliary circuit for each 10⁵ polarity responsive device including a source of current, a front contact of a stick relay and a front contact of a track relay of a track section associated with the next signal in advance.

2. In a railway signaling system of the direct current polar type, the combination with three condition signals at each of a plurality of points along the track, of a three condition polarity responsive device for each signal, two circuits for each polarity responsive device one energized by 15 current of one polarity and the other energized by current of another polarity and each including contacts of the next polarity responsive device in advance, an auxiliary circuit for each polarity responsive device including a front contact of a 20 stick relay and a front contact of a track relay of a track section associated with the next signal in advance, and means for picking up said stick relay upon completion of one of said two circuits.

3. In a railway signaling system of the direct current polar type, the combination with a three condition signal at each of a plurality of points along the track, of a three condition polarity responsive device for each signal, two circuits for each polarity responsive device one energized by 30 current of one polarity and the other energized by current of another polarity and each including contacts of the next polarity responsive device in advance, a relay included in series with one of 35 said two circuits, and a front contact of said 40 relay in multiple with said contacts of the next polarity responsive device in advance, whereby said relay will not drop upon opening said contacts of said next polarity responsive device in 45 advance.

4. A railway signaling system of the direct current polar type comprising, a track divided by insulating joints into blocks, a track relay for each block, a three condition polarity responsive device for each block, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive device in advance, a stick relay, a front contact of said relay in multiple with said contacts of said polarity responsive device next in advance, and means for picking up said stick relay upon completion of said clear circuit.

5. A railway signaling system of the direct current polar type comprising, a track divided by insulating joints into blocks, a track relay for each block, a three condition polarity responsive device for each signal, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive de- 65 70 75 80 85 90 95 98 99 100 101 102 103 104 105 106 107 108 109 110 111 112 113 114 115 116 117 118 119 120 121 122 123 124 125 126 127 128 129 130 131 132 133 134 135 136 137 138 - vice in advance, a relay included in series in said clear circuit, and a front contact of said relay in multiple with the contacts of the polarity responsive device included in said clear circuit.
5. A railway signaling system of the direct current polar type comprising, a track divided by insulating joints into blocks, a track relay for each block, a three condition polarity responsive device for each signal, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive device in advance, a stick relay picked up upon completion of said clear circuit, and a front contact of said stick relay in multiple with the contacts of the polarity responsive device included in said clear circuit.
6. A railway signaling system of the direct current polar type comprising, a track divided by insulating joints into blocks, a track relay for each block, a three condition polarity responsive device for each signal, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive device in advance, a stick relay picked up upon completion of said clear circuit, and a front contact of said stick relay in multiple with the contacts of the polarity responsive device included in said clear circuit.
7. A railway signaling system of the direct current polar type comprising, a track divided by insulating joints into blocks, a track relay for each block, a three condition polarity responsive device for each signal, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive device in advance, a stick relay picked up upon completion of said clear circuit, and a front contact of said stick relay in multiple with the contacts of the polarity responsive device included in said clear circuit, and an illuminating lamp for each signal having an energizing circuit including a back contact of the associated stick relay.
8. A railway signaling system of the direct current polar type comprising, a track divided by insulating joints into blocks, a track relay for each block, a three condition polarity responsive device for each signal, a clear circuit for each polarity responsive device including in series front contacts of the track relays of its block and the next block in advance and contacts of the polarity responsive device next in advance, a caution circuit for each polarity responsive device including in series contacts of the track relay of the block in advance and contacts of the next polarity responsive device in advance, a stick relay included in said clear circuit, and a stick contact of said relay in multiple with the contacts of the polarity responsive device included in said clear circuit, whereby the polarity responsive device next in advance must have its contacts closed to pick up its associated stick relay but the clear circuit will not be broken upon opening of such contacts.
9. A railway signaling system of the direct current polar type comprising, a signal of the quick acting three-position search light type having two position clear contacts closed when in its clear position and two position caution contacts closed when in its caution position, a clear circuit for each signal including a front clear contact or a front caution contact of the next signal in advance, a stick relay associated with each signal, and a caution circuit for each signal including a back contact of the stick relay associated with the next signal in advance.
75. 10. A railway signaling system of the direct

current polar type comprising, a signal of the quick acting three-position search light type having two position clear contacts lifted when in its clear position and two position caution contacts lifted when in its caution position, a clear circuit for each signal including either a front clear contact or a front caution contact of the next signal in advance, a stick relay associated with each signal, a caution circuit for each signal including a back contact of the stick relay associated with the next signal in advance, and a front contact of each of said stick relays for shunting the clear contact and the caution contact of its associated signal.

11. A railway signaling system of the direct current polar type comprising, a signal of the quick acting three-position search light type having two position clear contacts lifted when in its clear position and two position caution contacts lifted when in its caution position, a clear circuit for each signal including a front clear contact or a front caution contact of the next signal in advance, a stick relay associated with each signal having its winding included in series in the clear circuit of the next signal in the rear, and a front contact of each stick relay shunting the clear contact and the caution contact of its associated signal.

12. A signal system of the type described, comprising, in combination, a three unit light signal at each of a plurality of signal locations along the track, a polar relay for each signal for controlling the same, a control circuit for each polar relay including a contact of the next polar relay in advance and the winding of another relay located near said next polar relay in advance, and a front contact on said another relay for shunting said contact of the next polar relay in advance.

13. In a railway signaling system of the direct current polar type; the combination with three condition signals at each of a plurality of points along the track; of a three condition polarity responsive device for each signal; a lamp for each signal; two circuits for each polarity responsive device one energized by current of one polarity and the other energized by current of another polarity and each including contacts of the next polarity responsive device in advance; an auxiliary circuit for each polarity responsive device including a source of current, a front contact of a stick relay and a front contact of a track relay of a track section associated with the next signal in advance; and an energizing circuit for said lamp including a back contact of said stick relay.

14. A railway signaling system of the direct current polar type comprising, a signal of the quick acting three-position search light type including a lamp and having two-position clear contacts lifted when in its clear position and two-position caution contacts lifted when in its caution position, a clear circuit for each signal including either a front clear contact or a front caution contact of the next signal in advance, a stick relay associated with each signal, a caution circuit for each signal including a back contact of the stick relay associated with the next signal in advance, a front contact of each of said stick relays for shunting the clear contact and the caution contact of its associated signal, and a back contact of said stick relay for controlling energization of said lamp.

15. A railway signaling system of the direct current polar type comprising, a signal of the quick acting three-position search light type in-

cluding an electric lamp and having two-position clear contacts lifted when in its clear position and two-position caution contacts lifted when in its caution position, a clear circuit for each signal including a front clear contact or a front caution contact of the next signal in advance, a stick relay associated with each signal having its winding included in series in the clear circuit of the next signal in the rear, a front contact of each stick relay shunting the clear contact and the caution contact of its associated signal, and a back contact of said stick relay for controlling energization of said lamp.

16. A signal system of the type described, comprising in combination, a multiple unit light signal at each of a plurality of signal locations along the track, a polar relay for each signal for controlling the same, a control circuit for each polar relay including a contact of the next polar relay in advance and the winding of another relay located near said next polar relay in advance, a front contact on said another relay for shunting said contact of the next polar relay in advance, and a back contact of said another relay included in series with a common wire leading to the light signal units of said multiple unit light signal.

17. In a signal system of the character described; comprising in combination a signal at the entrance to each of a plurality of blocks; a polar relay for each signal; another relay for each signal; a clear circuit for each polar relay including in series front contacts of said polar relay at the next signal in advance, the winding of said another relay for the next signal in advance and a contact closed only if the second block in advance is unoccupied, and a shunt

branch circuit for said front contacts of such polar relay including a front contact of the associated another relay.

18. In a signal system of the character described; comprising in combination a signal at the entrance to each of a plurality of blocks; a polar relay for each signal; another relay for each signal; a clear circuit for each polar relay including in series front contacts of said polar relay at the next signal in advance, the winding of said another relay for the next signal in advance and a contact closed only if the second block in advance is unoccupied; a shunt branch circuit for said front contacts of such polar relay including a front contact of the associated another relay; and a caution circuit for each polar relay including a back contact of the polar relay and a back contact of the another relay for the signal next in advance.

19. In a signal system of the character described; comprising in combination a signal at the entrance to each of a plurality of blocks; a polar relay for each signal; another relay for each signal; a clear circuit for each polar relay including in series front contacts of said polar relay at the next signal in advance, the winding of said another relay for the next signal in advance and a contact closed only if the second block in advance is unoccupied; a shunt branch circuit for said front contacts of such polar relay including a front contact of the associated another relay; and an illuminating circuit for each signal including a back contact of its associated another relay.
